EXPANDABLE MANDREL FOR WEB REWINDERS

Peter Zernov, Milwaukee, Wis., assignor to Mercury Engineering Corporation, Milwaukee, Wis., a corporation of Wisconsin

Filed Jan. 26, 1959, Ser. No. 789,160

2 Claims. (Cl. 242—72)

This invention relates generally to paper converting machinery and more particularly to a mandrel for winding a roll of web material on a rewinder, for example, as it comes off a printing press or other machine.

In this particular art, the rolls of web material are of considerable size and weight. They also vary in length and it is therefore often necessary to change the position of the supporting arms of the rewinder to accommodate these various roll lengths.

After this web of material has been wound on a mandrel, it is desirable to pull the mandrel from the rolled material for reuse thereby minimizing the total number of mandrels required.

Contractible drums or mandrels have been used with a certain amount of success but have generally had several disadvantages. For example, many of them are comprised of numerous parts including cams and wedging devices and are of rather complicated and heavy structure which make them difficult to operate, more subject to malfunctioning and difficult to handle manually when empty. Other prior art collapsible reels or rollers of this general nature are comprised only of two sections which define the reel periphery and in the collapsed position to not actually or sufficiently reduce the diameter of the reel in all directions. Still other devices, because of their complicated internal mechanism, are not adaptable to be chucked at each of their ends by conventional chucking equipment.

In accordance with the present invention, an expandable-type mandrel has been provided which is economical to manufacture, relatively light in weight considering its size and strength requirement, easily reduced in diameter to permit ready withdrawal from the roll formed thereon, readily chucked into winding position, and can accommodate any length of roll material to be formed thereon without the necessity of readjusting the support arms of the rewinder.

More particularly, the present invention provides a three-section collapsible mandrel for a web rewinder, two sections of which are collapsibly connected together by over-center toggle linkage which is carried solely on adjacent longitudinal edges of these two sections. The result is a simple, rigid and efficient joint which leaves the interior of the mandrel unobstructed.

More specific aspects of the present invention contemplate an expandable mandrel of the above type which will maintain an assembled relationship of the various parts when in the collapsed position to thereby facilitate the handling thereof.

These and other objects and advantages will appear hereinafter as this disclosure progresses, reference being had to the accompanying drawings, in which:

Figure 1 is a perspective view into a mandrel made in accordance with the present invention;

Figure 2 is another perspective view of the mandrel, but on a smaller scale;

Figure 3 is a side view of the mandrel, certain parts being broken away and in section for clarity;

2

Figure 4 is an end view of the mandrel; and Figure 5 is a fragmentary sectional view taken on line 5—5 in Figure 3.

The present invention is concerned with an expandable mandrel for use with that general type of machine shown in the co-pending United States application Serial No. 762,646, filed September 22, 1958, issued as Patent No. 2,969,930, on January 31, 1961, and entitled "Continuous Rewinder For Web Material." For a more complete description of such a rewinder, and more particularly of the structure and operation of the chucking heads in which the present mandrel is mounted, reference may be had to that application if thought necessary or desirable.

However, referring more particularly to the drawings, it is thought only necessary to mention in regard to the rewinder itself, that a pair of axially-shiftable chucking heads 1 and 2 have an axially extending flange 3 on which the mandrel M is mounted for rotation therewith.

The mandrel comprises three sections 4, 5 and 6 which each constitute an arc of about 120° and which are connected together by the piano hinges 7 and 8 which are generally coextensive in length with these sections.

Over-center type toggle linkages connect sections 4 and 6 together at spaced locations along the length of the mandrel. These linkages may all be collapsed by a single tool from the end of the mandrel which causes a reduction in diameter thereof to permit ready removal of the mandrel from the roll of material. When these toggle linkages are straightened out, they securely lock the sections into a true circular cross-sectional shape. These actions are accomplished as follows.

A shaft 9 is rotatably secured adjacent the edge of the arcuate section 4 by means of the brackets 10 which are welded to the inner surface of this section and in which the shaft is oscillatably mounted. An arm 11 is located on each side of each bracket 10 and these arms are rigidly secured to the shaft 9 by set screws 12 for oscillation with the shaft.

Another shaft 15 is oscillatably mounted along the adjacent edge of arcuate section 6 by being freely mounted in the bifurcated brackets 16 welded to section 6 at spaced locations along the length thereof. An arm 17 is located in the bifurcated end of each one of the brackets 16 and are rigidly secured to the shaft 15 by set screws 18. Arms 17 extend between their adjacent pair of arms 11 and are pivotally connected thereto by a pin 20 held captive by set screw 21.

The arms 11 and 17 constitute toggle linkage which, as shown in Figure 4, are in the substantially straightened position slightly over dead-center where they act to lock the sections together in the expanded position.

A spring 22 located at each end of the mandrel and acting in tension between the shafts 9 and 15 firmly hold the toggle linkages in the slightly over dead-center position.

The linkages are held in the locked position and prevented from going further past dead-center by the stop lugs 23 (Figure 5) which are welded to shafts 9 and 15 and bear against the inner surfaces of their sections when the toggle linkage reaches the locked position shown. These lugs insure precise alignment of the sections in this expanded position and contribute to a rigid and concentric mandrel.

One end of shaft 9 terminates in a square portion 25 which receives a complementary-shaped socket wrench by which the shaft 9 is oscillated between the locked position shown in Figure 4 and an unlocked position wherein the pivot pins 20 go over center toward the center of the mandrel. The shaft 9 acts as a torsion bar in actuating all of the toggle linkages.

Provision is made for guiding the adjacent edges of sections 4 and 6 in their movement towards and away

from one another, and for also preventing collapse of the sections when the mandrel is empty. This guiding means takes the form of arcuate guide bars 27 and 28 welded or otherwise secured at one of their ends to sections 4 and 6, respectively, and extend over the other section. These guide bars 27 and 28 are located at both ends of the mandrel and also help to insure alinement of the section edges and reinforcement thereacross. In addition, they insure alinement of the sections in the axial direction. The chucks 1 and 2 prevent collapse of the sections when the mandrel is loaded and the guides 27 and 28 perform this function when the chucks are not in place and the mandrel is empty.

The outer ends of the sections 4, 5 and 6 are reinforced by the arcuate-shaped rod members 30 which are fastened thereto by screws 31. Members 30 are co-extensive with the sections in radial extent and form a smooth peripheral surface therewith. The inner corner of these members 30 are chambered to facilitate entry therein of the chuck heads 1 and 2.

Drive slots 34 are formed in each end of the mandrel for receiving the drive lugs 35 of the chucks. These slots are formed through adjacent corners of the sections and through the reinforcing members 30.

It will be noted that when the mandrel is expanded, the space between the sections 4 and 6 is irregular or broken along the length of the mandrel which offers a smooth rolling contact for the presser roll (not shown) to travel over. There is thus no abrupt change from one section to the next.

The mandrel made in accordance with the present invention provides for readily reducing its diameter by approximately $\frac{1}{8}$ of an inch as shown in the drawings, for easy withdrawal from the rolled material. No shims or tapered connections are required and the structure is simple and relatively light in weight. A smooth-acting and accurate mandrel with positive locking and unlocking thereof has been provided which can be quickly operated to accommodate various lengths of rolls to be formed thereon.

Various modes of carrying out the invention are contemplated as being within the scope of the following claims particularly pointing out and distinctly claiming the subject matter which is regarded as the invention.

I claim:

1. A tubular and expandable mandrel for being removably mounted between the chuck heads of a web re-winder, said mandrel comprising, three elongated arcuate-shaped sections, two of said sections being hingedly connected along one of their longitudinal edges to opposite edges of the third section, said two sections being shift-

ably secured together by a toggle linkage assembly, said assembly including a shaft oscillatably mounted within said mandrel and along the inside of each of the adjacent longitudinal edges of said two sections, a series of axially-spaced toggle links connected between said shafts, one of said links of each series being rigidly secured to one of said shafts, means on said one shaft for receiving a tool to oscillate said one shaft and said toggle links into collapsed and substantially dead-center positions to thereby respectively contract and expand the mandrel, and pairs of arcuate guide bars, one bar of each pair being rigidly secured to each of said two sections adjacent the longitudinal edges of said two sections for sliding and guiding contact with said two sections, the bars of each pair being adjacent one another.

2. A tubular and expandable mandrel for being removably mounted between the chuck heads of a web re-winder, said mandrel comprising, three elongated arcuate-shaped sections, each section having a chuck head receiving reinforcing rim at their ends, two of said sections being hingedly connected along one of their longitudinal edges to opposite edges of the third section, said two sections being shiftably secured together by a toggle linkage assembly to thereby vary the diameter of said mandrel, said assembly including a shaft oscillatably mounted within said mandrel and along the inside of each of the adjacent longitudinal edges of said two sections, a series of axially-spaced toggle links connected between said shafts, means on one of said shafts for receiving a tool to oscillate said one shaft and said links into collapsed and substantially dead-center positions located completely within the periphery of said sections to thereby respectively contract and expand the mandrel, and pairs of arcuate guide bars, one bar of each pair being rigidly secured to each of said two sections adjacent the longitudinal edges of said two sections for sliding and guiding contact with said two sections, the bars of each pair being adjacent one another.
